(57) **CLAIM**

I claim the ornamental design for a water bottle, as shown and described.

DESCRIPTION

FIG. 1 is a top perspective view of a water bottle in its open configuration showing my new design;

FIG. 2 is a side elevational view thereof;

FIG. 3 is a front elevational view thereof;

FIG. 4 is a rear elevational view thereof;

FIG. 5 is a top view thereof;

FIG. 6 is a side elevational view thereof in its closed configuration; and,

FIG. 7 is a front elevational view of FIG. 6.

The broken lines in the drawing depict portions of the water bottle that form no part of the claimed design.
